United States Patent Office

Des. 184,542
Patented Mar. 3, 1959

184,542

WATCH

Marshall Tulin, Hewlett, N. Y.

Application May 2, 1958, Serial No. 50,733

Term of patent 14 years

(Cl. D42—8)

Fig. 1.

Fig. 2.

Fig. 3.

Fig. 1 is a side view of a watch showing my new design;
Fig. 2 is a top plan view thereof; and
Fig. 3 is a bottom plan view thereof.

The dominant features of my design reside in the portions shown in full lines.

I claim:

The ornamental design for a watch, substantially as shown and described.
